MARINE TYPE STEAM BOILER

Filed Sept. 24, 1921

Inventor

C. G. Hawley

Patented Jan. 3, 1928.

UNITED STATES PATENT OFFICE.

CHARLES GILBERT HAWLEY, OF CHICAGO, ILLINOIS.

MARINE-TYPE STEAM BOILER.

Application filed September 24, 1921. Serial No. 503,065.

This application is companion to my applications S. N. 500,107 and S. N. 503,064, of Sept. 12, 1921, and Sept. 24, 1921, respectively, and has to do with a new boiler closely akin to those of said applications but which, under certain circumstances and for certain uses, is more compact, of less weight and generally more economical.

This present invention comprises a bank 10 of water tubes and the upper and lower drums belonging thereto, in combination with a plurality of cylindrical header drums that extend from the side of the upper drum of the tube bank, and a substantially 15 triangular water-wall for and in communication with each said header drum, the same in each case depending from such header drum and having a bottom or lower end which terminates in a relatively small 20 intake or neck which opens through the side of the lower drum of the tube bank. Various additional features of my invention will appear hereinafter.

The invention will be readily understood 25 on reference to the accompanying drawings, in which Fig. 1 is a front elevation of a steam boiler embodying my invention, partly in vertical cross section on the line 1—1 of Fig. 2; Fig. 2 is a vertical longitudinal 30 section of the boiler, on line 2—2 of Fig. 1; and Fig. 3 is a detailed view of a modified form of a water wall.

The before mentioned bank of vertical water tubes is indicated by the reference number 2. The upper drum is marked 3 and the lower drum is marked 4, both belonging 35 to the bank of tubes. The parts 5 are the cylindrical header drums which, as shown, communicate with or enter the side of the upper drum 3. The parts 6 are the before 40 mentioned water walls, one for each header drum 5 and each presenting a slanting, bulbous bottom 6' that terminates in an intake 6'' which communicates with or opens 45 through the side of the lower drum 4.

When desired, the slanting bottom 6' of each water wall, may, at the front end, terminate in a blow-off neck 6''', or, if desired, each of these substantially triangular 50 water walls may partake of a more truly triangular shape, and have a bottom which extends uninterruptedly from the intake neck 6'' to the front end of its respective header drum 5. This arrangement is shown 55 clearly in Fig. 3.

7 represents the steam outlet of the boiler. The parts 8 are hand-holes which I provide in the top of the drums 5 and in the top of the drum 3 to facilitate the cleaning of the internal surfaces of the boiler by means 60 of the tools introduced therethrough. The part 9 is a blow-off connection for the lower drum. The feed water may enter through the upper or the lower drum.

The pressure vessel thus described is enclosed within refractory walls 10 which constitutes the setting thereof.

The forward chamber 11 constitutes the fire chamber and contains the several vertical water walls, 6. The heat of the fire 70 in the chamber 11 is directly communicated to the extensive surfaces of the water walls and thereby a vigorous circulation of boiler water is set up; downward through the tubes 2, and upward through the water 75 walls 6.

A boiler of this design will be found to be of high capacity and reasonably high efficiency. If it is desired to further increase the efficiency of the boiler, a second 80 bank of tubes 2' with drums 3' and 4', is added thereto, within the boiler setting. The parts marked 12, 13, and 14 are suitable cross connection pipes between the two 85 banks of tubes.

The parts marked 15 are baffles which compel the hot gases from the fire chamber to traverse all of the tubular surfaces of the boiler before escaping at the outlet 16.

The parts 17 and 17' are a blow-off connection and blow-off valve, for the several parts 6''', of the water walls.

It is to be understood that each water wall is formed of relatively thin boiler plate and 90 that the flat sides thereof are connected by many, properly spaced staybolts, as shown.

Any desired arrangement of baffles 18 may be employed in the fire chamber proper, the same finding support upon and between the 100 several water walls.

It is to be noted that the drums 3, 3', and 5 mainly constitute the roof of the fire chamber. The roof is completed by brick slabs, 19, and a covering, 20, of non-conducting 105 material, as well shown in the drawings.

The advantage of this construction, aside from the circulation enforced by the water walls, lies in the fact that I thus make it possible to advantageously assemble a max- 110

imum aggregate of heating surface, within a boiler setting of given dimensions. Having thus described my invention I claim as new and desire to secure by Letters Patent:

- 5 1. A steam boiler comprising an upright bank of tubes and the upper and lower cross drums belonging thereto, in combination with a plurality of longitudinal header drums, perpendicular to the upper cross 10 drum and opening into the side thereof, a longitudinal and vertical water wall for each said header drum and opening into the bottom thereof, each said wall having an inclined bottom, the lower end of which forms 15 an intake neck and means placing the intake neck of each said water wall in communication with said lower cross drum.
2. A steam boiler comprising a convected heat absorbing portion having a steam and 20 water cross drum at its top, in combination with a plurality of header drums projecting from the side of said cross drum, a plurality of vertical radiant heat absorbing water walls positioned beneath respective 25 header drums, the horizontal length of said walls substantially equalling the length of said header drums and the top of each water wall opening into the bottom of its header drum, each said wall having an inclined bottom, the lower end of which forms an intake 30

neck, such intake neck joining the lower corner of each water wall to the lower part of said convected heat absorbing portion.

3. A fire chamber of a height permitting the substantially complete maturity of the flames of combustion, in combination with a steam boiler comprising a convected heat absorbing portion of major superficial extent occupying the rear portion of said chamber, parallel header drums in perpendicular communication with the top of said convected heat absorbing portion and occupying and partly forming the top of said fire chamber flame partitioning, radiant heat absorbing water walls positioned vertically in said fire chamber beneath respective header drums, said walls being in open communication with respective header drums substantially throughout the length thereof, the bottom of each said wall being downwardly and rearwardly inclined and terminating in an intake neck, and each said neck being in open communication with the lower part of said convected heat absorbing portion.

In testimony whereof, I have hereunto set my hand this 22nd day of September, 1921.

CHARLES GILBERT HAWLEY.
